(57) **CLAIM**

The ornamental design for a lamp assembly, as shown and described.

DESCRIPTION

FIG. 1 is a front, left elevational view of a lamp assembly showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front elevational view of the lamp body of the lamp assembly, shown separately for ease of illustration;

FIG. 9 is a front view thereof;

FIG. 10 is a top plan view thereof;

FIG. 11 is a bottom plan view thereof;

FIG. 12 is a bottom elevational view thereof;

FIG. 13 is a front elevational view of the lamp body shown without the lampshade for ease of illustration;

FIG. 14 is a front view thereof;

FIG. 15 is a rear view thereof;

FIG. 16 is a left side view thereof;

FIG. 17 is a right side view thereof;

FIG. 18 is a front, top elevational view of the base of the lamp assembly, shown separately for ease of illustration;

FIG. 19 is a front view thereof;

FIG. 20 is a rear view thereof;

FIG. 21 is a left side view thereof;

FIG. 22 is a right side view thereof;

FIG. 23 is a top plan view thereof;

FIG. 24 is a bottom elevational view thereof; and,

FIG. 25 is an enlarged view of the portion of FIG. 18 outlined by the dot-dash broken line.

The dash-dash broken lines shown in the drawings illustrate portions of the article. The dash-dot-dash broken lines demarcate the enlarged views; all broken lines form no part of the claimed design.
